Primary Examiner — Llorellys Martinez

(74) Attorney, Agent, or Firm — J. Greg Tinch, Esq.

(57) **CLAIM**

The ornamental design for a wristband with aperture, as shown and described.

DESCRIPTION

FIG. 1 is a top perspective view of a wristband with aperture in accordance with the present invention;

FIG. 2 is a front view thereof;

FIG. 3 is a rear view thereof;

FIG. 4 is a top view thereof;

FIG. 5 bottom view thereof;

FIG. 6 is a left side view thereof; and,

FIG. 7 is a right side view thereof.

The broken lines shown represent the portions of the wristband with aperture that form no part of the claimed design.
